UNITED STATES PATENT OFFICE.

LEWIS W. HOLMES AND CORNELIUS V. TRAUTMAN, OF MEDORA, INDIANA.

CONTROLLING ATTACHMENT FOR HEATING-LAMPS.

No. 883,883.

Specification of Letters Patent.

Patented April 7, 1908.

Application filed April 24, 1907. Serial No. 370,055.

To all whom it may concern:

Be it known that we, LEWIS W. HOLMES and CORNELIUS V. TRAUTMAN, citizens of the United States, residing at Medora, in the 5 county of Jackson and State of Indiana, have invented a new and useful Controlling Attachment for Heating-Lamps, of which the following is a specification.

This invention relates to controlling attachments for heating lamps such as used in connection with incubators and its object is to provide thermostatically controlled means for increasing or reducing the size of the flame so that the temperature within the incubator may be maintained uniform.

Another object is to provide simple and efficient means for adjusting the attachment so as to maintain any desired degree of heat within the incubator.

With these and other objects in view the invention consists of certain novel features of construction and combinations of parts which will be hereinafter more fully described and pointed out in the claims.

In the accompanying drawings is shown the preferred form of the invention.

In said drawings: Figure 1 is a section through a portion of an incubator and showing the attachment in elevation; Fig. 2 is a 30 plan view of the attachment; and Fig. 3 is a detail view of the flame controlling lever.

Referring to the figures by characters of reference, 1 designates the body of an incubator or the like from which extends a bracket 2 designed to support a heating lamp 3. A cross strip 4 is carried by this bracket and has upstanding ears 5 and 6, the ears 5 constituting bearings for a rod 7 while the ears 6 serve to prevent longitudinal displacement 40 of the rod. An arm 8 extends from the rod 7 at right angles thereto and carries a rectangular sleeve 9 which loosely surrounds a burner 10 of the heater 3. Another arm 11 extends in the opposite direction from rod 7 45 and carries a counterbalance 12. Stop lugs 13 are supported beneath the arms 8 and 11 so as to limit their swinging movement. A bail-like extension 14 extends upward from the rod 7 and is for the purpose hereinafter 50 set forth.

Secured upon the body 1 and above bracket 2 is an angular bracket 15 from which extends a guide plate 16 having in-

turned flanges 17 at the sides thereof. A slide 18 is mounted between these flanges 55 and has an upstanding ear 19. A plate 20 extends upward from bracket 15 and slidably mounted within it is an adjusting screw 21 which is connected to ear 19 and is engaged by an adjusting nut 22. A coiled 60 spring 23 is arranged upon the screw 21 and bears at its ends on plate 20 and ear 19. Ears 24 extend downward from the slide 18 and bearing within them is the upper end of a lever 25 having a fork 26 at its lower end 65 which loosely engages the bail 14. An eye 27 is formed within this lever between its ends and is engaged by one end of a link 28. The other end of this link engages an ear 29 formed at one end of a thermostat 30. This 70 thermostat is in the form of a bowed metallic strip secured at one end within the body 1 and formed of material which will readily expand when heated.

It is to be understood that when the p rts 75 are in their normal positions the wick 31 of the burner is exposed so that the flame will not be confined or restricted. When, however, the thermostat is subjected to a predetermined heat it will pull inward on link 28 80 and lever 25 and swing the bail 14 so as to raise arm 8 and sleeve 9. The sleeve will reduce the size of the flame and as the thermostat cools the parts will return to their initial positions. It is obvious that by adjusting the slide 18 the parts can be regulated 85 so as to maintain any desired temperature within the body 1. By arranging the parts in the manner shown and described the movement of the thermostat is greatly 90 multiplied so that a very slight expansion or contraction of the thermostat will cause a considerable movement of sleeve 9.

What is claimed is:

The combination with a supporting structure and a bracket extending therefrom for supporting a heater; of a cross strip connecting opposite portions of the bracket, upstanding bearing ears thereon between the ends thereof, upstanding retaining ears thereon adjacent the ends thereof, oppositely disposed stop lugs integral with the cross strip, a rod detachably mounted upon the bearing ears and held against longitudinal movement by the retaining ears, an arm extending perpendicularly from said rod, a sleeve carried 100

by the free end of said arm, an arm extending in the opposite direction from the rod, a counterbalance thereon, an upstanding bail upon the rod, and a thermostatically controlled lever pivotally connected to the supporting structure and having a forked end engaging the bail.

In testimony that we claim the foregoing

as our own, we have hereto affixed our signatures in the presence of two witnesses.

LEWIS W. HOLMES.
CORNELIUS V. TRAUTMAN.
